UNITED STATES PATENT OFFICE.

ASA H. THOMPSON, OF GROTON, MASSACHUSETTS.

FIRE-EXTINGUISHER.

SPECIFICATION forming part of Letters Patent No. 761,726, dated June 7, 1904.

Application filed February 12, 1904. Serial No. 193,323. (No model.)

To all whom it may concern.

Be it known that I, ASA H. THOMPSON, of Groton, in the county of Middlesex and State of Massachusetts, have invented certain new and useful Improvements in Fire-Extinguishers, of which the following is a specification.

My invention relates to fire-extinguishers of the class which are employed in putting out field or ground fires; and it consists in certain novel features of construction, arrangement, and combination of parts, which will be readily understood by reference to the description of the accompanying drawings, forming a part of this application, and to the claims hereto appended, and in which my invention is clearly pointed out.

Figure 1 of the drawings is a plan of a fire-extinguisher illustrating my invention with a portion of the outside covering of the main drum and the wire-netting support therefor broken away in order to more clearly show other parts. Fig. 2 is a longitudinal section of the same on line A A on Figs. 1 and 3. Fig. 3 is an end elevation looking at the left end of Fig. 1. Fig. 4 is an end elevation looking at the right end of Fig. 1, and Fig. 5 is a transverse section illustrating a modification.

In the drawings, 1 1 are two spoked wheels mounted loosely on the shaft 2, said wheels being connected together by suitable stay-rods 3 to maintain them at a proper distance apart, and a wire-netting covering 4 is wrapped around said wheels and extends from one wheel to the other in the form of an open-work cylinder, said netting being secured together at its longitudinal edges and also firmly secured to the circular rim or tire of said wheels in any suitable manner. An outer covering 5, of felt or a loosely-woven asbestos fabric, is wrapped about and firmly secured to said netting.

The shaft 2 has firmly secured thereon, so as to be movable therewith about the axis of said shaft, a metal cylinder 6, one head of which is set a short distance inside of the end of the barrel of said cylinder to form a pan-like recess 7 to facilitate the filling of the said cylinder with water or other liquid.

The cylinder 6 has its bearings on the shaft 2 slightly above the centers of its heads,

whereby said cylinder will be maintained automatically in its normal position when not in operation—that is, with the discharge-⁵⁵ orifices 8 arranged in a longitudinal row or rows along one side thereof uppermost. The chambered end of said cylinder 6 is provided with a feed-orifice 9, which communicates with the elbow-pipe 10, located just inside of said recessed head, and extends from said feed-orifice nearly to the opposite side of the barrel of said cylinder, as shown in full lines in Fig. 2 and in dotted lines in Fig. 3.

One end of the shaft 2 has firmly secured thereon outside of a wheel 1 a lever 14, as shown in Figs. 1 and 4. The shaft 2 also has loosely mounted on each end thereof one arm of a forked pole or handle 11, made, preferably, in three parts, bolted together, as shown in Figs. 1, 3, and 4.

The operation of my invention is as follows: The machine is first turned up so as to rest upon its right-hand end. Water or other fire-extinguishing liquid is then poured into the pan-like recess 7 and will flow through the feed-orifice 9 and the pipe 10 till the cylinder 6 is filled, when the machine is turned down upon its side and the cylinder 6 assumes its normal position, with its heaviest portion below the axis of its shaft 2 and the perforations 8 at the top or upper side of said cylinder. The operator then seizes the handle and pushes the machine toward the fire, the covered drum rolling on the ground while the cylinder 6 maintains its normal position.

When the vicinity of the fire is reached, the operator imparts a half-revolution to the cylinder 6 by moving the lever 14 from its position shown in Figs. 1 and 4 to a position alongside of an arm of the forked pole or handle 11 and secures said lever 14 to said arm by a pin (not shown) inserted through the holes 15 and 16, formed, respectively, in the arm of the handle and in the end of said lever. When this is done, the water in the cylinder will be discharged, through the orifices 8, into the annular space between the cylinder 6 and the wall of the main drum, thereby thoroughly saturating the felt or asbestos covering 5, the quantity of liquid discharged

from said cylinder being proportioned to the 95 100

size and number of the orifices 8. The machine with its covering so saturated and with more or less liquid percolating through said covering being rolled over a ground-fire will 5 effectually extinguish the same.

Instead of hanging the cylinder 6 out of center it may be mounted in bearings concentric with its axis, and the side of said cylinder opposite to the discharge-orifices may be weighted by securing therein a bar of metal 18 of suitable capacity to insure said cylinder being normally maintained in a position with its discharge-orifices at its top side, as illustrated in Fig. 5.

15 What I claim as new, and desire to secure by Letters Patent of the United States, is—

1. In a fire-extinguisher, the combination of a hollow drum the circumferential shell of which is composed of an open-work metal 20 structure and an outer covering of porous textile fabric preferably asbestos, and adapted to roll upon the ground; a shaft having bearings in the heads of said drum; a liquid-receiving tank firmly secured upon said shaft, and provided on one side with a series of discharge-orifices distributed longitudinally along one side thereof; means for normally holding said tank, with its perforated side uppermost; means for reversing said tank and securing it 25 in said reversed position; and means by which the machine may be propelled over the burning ground.

2. In a fire-extinguisher, the combination of a supporting-drum having a porous peripheral 30 wall and wheel-like heads mounted loosely on a shaft or journals; a liquid-receiving cylinder provided with a series of discharge-orifices distributed longitudinally along one side thereof; a journal secured to and projecting

outward from each head of said cylinder and 40 fitted to bearings in the heads of said drum; a reversing-lever firmly secured on one of said journals; a pole or operating-handle mounted loosely on said journals; and means for securing said reversing-lever and pole together as 45 and for the purposes set forth.

3. In a fire-extinguisher, the combination with a revoluble drum having a porous peripheral wall; of a liquid-receiving cylinder provided with eccentric journals on its ends 50 fitted to axial bearings in the heads of said drum, and with a pan-like recess or chamber in one end thereof, and a series of perforations distributed longitudinally along one side thereof; and a supply-pipe extending transversely across the interior of said receiving-cylinder, and communicating at one end with the pan-like chamber 7, and open at its other end to the interior of said cylinder.

4. In a fire-extinguisher, the combination 60 with a revoluble drum having a porous peripheral wall, and means for propelling said drum along the ground, of a liquid-receiving cylindrical tank having journals fitted to bearings in the heads of said drum, and provided 65 with a series of discharge-orifices distributed longitudinally along one side thereof, said tank being so constructed and arranged that the preponderance of weight thereof shall be upon the side of its axis opposite to said discharge-orifices as and for the purposes set forth.

In testimony whereof I have affixed my signature in presence of two witnesses.

ASA H. THOMPSON.
